(57) **CLAIM**

The ornamental design for a tool holder, as shown and described.

DESCRIPTION

FIG. 1 is a front perspective view of a first embodiment of a tool holder showing our new design;

FIG. 2 is a front perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front perspective view of a second embodiment of a tool holder showing our new design;

FIG. 10 is a rear perspective view of a third embodiment of a tool holder showing our new design; and,

FIG. 11 is a front perspective view of a fourth embodiment of a tool holder showing our new design.

The dashed broken lines in the drawings are for environmental purposes only and form no part of the claimed design.
